cut #15, Pilsner.

FIGURE 1 is a side elevational view of a combination beer glass and cocktail shaker showing my new design and with the base member attached to the lower portion of the body;

FIGURE 2 is a side elevational view thereof but with the base portion on the top of the body;

FIGURE 3 is a bottom plan view of the base portion;

FIGURE 4 is a plan view of the device shown in FIGURE 1;

FIGURE 5 is a bottom view of the body portion.

I claim:

The ornamental design for a combination beer glass and cocktail shaker, as shown.
